UNITED STATES PATENT OFFICE

HALVARD F. NYGARD, OF MADISON, WISCONSIN, ASSIGNOR TO BURGESS BATTERY COMPANY, OF MADISON, WISCONSIN, A CORPORATION OF WISCONSIN

HAND LAMP

Application filed June 19, 1928. Serial No. 286,620.

My invention relates to a battery hand lamp which consists of a dry cell battery with a cup at the top thereof, the cup containing an incandescent bulb in a separable head so constructed as to be capable of being flipped by the thumb or finger into either the operative or inoperative position.

My invention relates to improvements in the hand lamp disclosed and claimed in the application of John S. Zook, Serial No. 225,045, filed October 10, 1927 (now Patent No. 1,701,093, granted February 5, 1929). It is an object of my invention to provide a hand lamp of the type described in said application wherein the incandescent bulb is removably and adjustably mounted in the separable head. It is a further object of my invention to provide a socket holder which, in the inoperative position, will fit closely over the top edges of the cup and present a more finished appearance. Further objects and advantages will be made clear by the following detailed description, which is to be taken in conjunction with the accompanying drawings, wherein:

Fig. 1 illustrates in part sectional elevation the whole of the battery hand lamp with the incandescent bulb in solid lines for the operative position and in dotted lines for the inoperative position;

Fig. 2 illustrates in part sectional elevation the separable head with the socket in full lines for the normal position and in dotted lines for the position permitting the insertion or removal of the bulb;

Figs. 3 and 4 are side and end views respectively of the sheet metal backing member comprising my improved socket holder;

Figs. 5, 6, and 7 are various views of the bulb socket.

Fig. 8 is a sectional view of a modified bulb socket which carries a connecting member in its lower end.

In the preferred form of my invention, I employ a battery consisting of one or more dry cells 1 and 2 electrically connected as by connector 3. The battery is arranged in a suitable carton 4, which may be of paper, and which projects above the top of the dry cells 50 to form an oval cup. In this cup I place a

metallic cup 5, which is electrically connected to one of the poles of the battery, preferably by soldering to the negative can as at 6. An opening 7, in the bottom of the metallic cup 5 allows the other pole, preferably the positive 8, to be exposed. The second pole must be insulated from the cup, as by a sheet of insulating paper 9. This sheet of insulating paper may be extended and bent down to form an insulating separating sheet 10 between cells 1 and 2, in which case the cells need not have individual paper wrappers over the zinc cans. A layer of fusible sealing material 11 may rest upon the bottom of carton 4 and the lower ends of cells 1 and 2 may be imbedded therein. The side edges of opening 7 are bent up, as at 12, for a purpose to be explained hereinafter. At the end of the cup opposite to opening 7, wings 13 are formed as by punching in the sides of the cup 5, the purpose of these wings to be explained hereinafter. A small lug 14 is formed on the bottom of the cup at the end removed from opening 7, as by stamping the metal.

An incandescent bulb 15 is mounted, as by screwing, in bulb socket 16 which is shown in detail in Figs. 5, 6 and 7. The socket 16, preferably of sheet metal, is cylindrical in form with one side longitudinally open, as at 17. The edges of opening 17 are provided with outwardly projecting flanges 18. The opposite side of the socket may contain circular opening 19. Grooves or threads 20, conforming to the pitch of the threads on the base of bulb 15, and outwardly projecting lugs 21 are provided in the socket.

The bulb socket 16 is carried by a holder consisting of a backing member 22 which is fashioned, as by stamping, from a single piece of material preferably sheet metal and has two integral cams 23 depending from the sides thereof (see Fig. 3). Each cam 23 contains raised portion 24 in which a hole 25 is stamped or drilled. Adjacent one side of raised portion 24 and spaced slightly therefrom is a hole 26. Adjacent the other side of raised portion 24 is an inwardly stamped lug 27 which may be longitudinal as shown or may be round. Socket 16 is mounted between cams 23 by inserting lugs 21 into holes 26. 100

Socket 16 is thus free to pivot into positions such that its axis is perpendicular or parallel to backing member 22 as shown in dotted and full lines respectively in Fig. 2. When socket 16 is perpendicular to backing member 22, as shown in dotted lines in Fig. 2, bulb 15 may be screwed into or out of said socket 16. Assuming that the bulb has been screwed into the socket, the latter is then swung into the parallel position shown in full lines. Lugs 27 compress socket 16 and squeeze it together sufficiently to make it difficult to turn bulb 15. The compressibility of socket 16 is facilitated by circular opening 19. Lugs 27 exert compression upon the sides of socket 16 slightly to one side of their middle portion and cause flanges 18 to press against backing member 22 thereby simultaneously holding the bulb in position and locking it in the socket. To remove or adjust the position of the bulb, the thumb or finger is wedged between the bulb 15 and backing member 22 and the bulb swung back into the dotted position of Fig. 2, in which position the bulb can be readily unscrewed from its socket as it is free from pressure exerted by lugs 27.

Looped spring 31 of Fig. 2, preferably of wire, is bailed to holes 25 in cams 23. Raised portions 24 allow the stub ends of spring 31 to move from one position to another without interfering with socket 16. The holder pivots on this bail when it is flipped from the operative to the inoperative position and vice versa.

Fig. 8 illustrates a modification which I may choose to embody in my preferred form of socket. The lower edge of the socket 16 may contain flange 28. Upon the ledge formed by flange 28, I may support circular disc 29 of bakelite, heavy paper, or other suitably rugged insulating material. Disc 29 is provided with a small central hole in which is fitted a metallic connecting member 30. Bulb 15 is adapted to be screwed down into socket 16 so that its end terminal is maintained in contact with connecting member 30.

The holder cooperates with the battery having the cup 5 mounted as described by slipping the looped spring wire 31 underneath wings 13 and over lug 14 so that the base of bulb 15 will contact with the terminal of the battery exposed through opening 7 when the head is in the position shown in solid lines in Fig. 1. The pressure of wings 13 insures a good contact between the base of bulb 15 and the exposed pole 8 of the battery. In the event that the construction shown in Fig. 8 is used the above mentioned contact is established by means of connecting member 30. Since the cup is electrically connected to one pole of the battery at 6, electrical connection is made to the screw thread of the lamp through socket 16 which is in contact with the backing member 22 in several places, the member 22, in turn, being in contact with cup

5 at several points. When the holder moves from one position to the other the corners of cams 23 slide on the bottom of cup 5 and pass beyond the opening 7. The turned-up edges 12 prevent the corners of cams 23 from slipping into opening 7. To put the hand lamp in the inoperative position the backing member 22 is flipped forward to the position shown by broken lines in Fig. 1. The looped spring 31, which remains in practically the same position during this operation, by its cooperation with lug 14, prevents the backing member 22 from interfering with the sides of cup 5 which are always in close proximity. The end terminal of bulb 15 is then no longer in contact with exposed pole 8 of the battery, and the bulb is no longer lighted. The looped spring 31 still acts to maintain the holder firmly in position. The corners of cams 23 are so shaped that when the holder is flipped into either position it assumes such position with a snap since the spring pressure is greatest at the intermediate position. This insures against the holders being in any other position than the operative or the inoperative positions and, furthermore, prevents the holder from being readily moved into the operative position to accidentally light the bulb while the hand lamp is being carried in the pocket or elsewhere. When the holder is in the inoperative position, the backing member 22 covers the top of the cup, fitting very closely along the edges of the cup, and forming a closure therefor. Lip 32 projects slightly beyond the end of cup 5 as shown in dotted lines in Fig. 1. The lip 32 thus acts as a stop for the holder when it has reached the proper inoperative position and protects the bulb against injury by shock during the act of flipping the holder into the inoperative position or in the event that the hand lamp is accidentally struck against a rigid object. When in the operative position backing member 22 acts as a reflector and may be polished or plated to enhance its value in that respect.

Repeated operation of the holder exerts a hammering effect upon pole 8 of cell 2 and, when the cells rest upon the bottom of carton 4, the hammering tends to drive cell 2 lower than cell 1 with the result that the end terminal of bulb 15 may soon fail to make contact with pole 8. Layer of sealing material 11 provides a more rigid base for the cells and overcomes the above named objection.

In the operative position the lower end of backing member 22 rests against the ends of turned up edges 12 which act as a stop. The bulb may be further adjusted so that, in this position, the base terminal contacts with terminal 8, thus providing proper contact and a two point suspension for the lamp head.

I claim:

1. In a battery hand lamp, a battery, a cup

above the top of said battery, a socket holder in said cup, said holder comprising a sheet metal backing member having integral cams depending from the sides thereof, an open-sided cylindrical metallic threaded bulb socket pivotally mounted between said cams, an incandescent bulb removably mounted in socket, means comprising outwardly stamped lugs in said socket cooperating with holes in said cams to pivot the axis of said socket into positions substantially parallel and perpendicular respectively to said backing member, and means comprising inwardly stamped lugs in said cams to compress said socket when in said parallel position to prevent the turning of said bulb within said socket.

2. In a battery hand lamp, a battery, a cup above the top of said battery, a socket holder in said cup, said socket holder comprising a backing member, cams depending from the sides of said backing member, a cylindrical bulb socket pivotally mounted upon said cams, an incandescent bulb removably mounted in said socket, means in said socket to pivot the axis thereof substantially parallel and perpendicular respectively to said backing member, and means in said cams to compress said socket when in said parallel position and to maintain said socket in said parallel position.

3. In a battery hand lamp, a battery, a cup above the top of said battery, a socket holder in said cup, a bulb socket pivotally mounted upon said socket holder, and an incandescent bulb mounted in said socket, said bulb being removable when said socket is in one position and being incapable of removal when said socket is in a second position with respect to said holder.

4. A separable head for a hand lamp battery comprising a socket holder, a bulb socket pivotally mounted in said holder, a means in said holder cooperating with means in said socket to retain said bulb firmly in place within said socket when said socket is in one position, said bulb being readily removable from said socket when said socket is in a second position with respect to said holder.

5. A separable head for a hand lamp battery comprising a holder, a bulb socket pivotally mounted in said holder, and a bulb mounted in said socket, said socket, when in one position, being adapted to lock said bulb in place, and while in a second position, to permit said bulb to be easily removed.

6. A separable head for a hand lamp battery comprising a socket holder, a bulb socket mounted in said holder, an incandescent bulb removably mounted in said socket, co-operating means in said socket and said holder to allow adjustment of the position of said bulb in said socket and to lock said bulb in said adjusted position.

7. In a battery hand lamp, a battery, a cup above the top of said battery, a socket holder

and socket in said cup, an incandescent bulb removably mounted in said socket, cooperating means in said socket and said holder to allow adjustment of the position of said bulb in said socket and to lock said bulb in said adjusted position.

8. In a battery hand lamp, a battery, a socket holder mounted on said battery, a bulb socket pivotally mounted in said holder, and a lamp bulb mounted in said socket, said lamp being removable from said socket when said socket is in one position and being incapable of removal when said socket is in a second position with respect to said holder, said socket holder and bulb being adapted to be moved to an operative or inoperative position.

9. A separable head for a hand lamp comprising a holder, a bulb socket pivotally mounted in said holder and adapted to be moved into positions substantially parallel and substantially perpendicular respectively to said holder, and cooperating means on said socket and said holder to maintain said socket in said parallel position.

In testimony whereof I affix my signature.
HALVARF F. NYGARD.
